UNITED STATES PATENT OFFICE

2,555,488

DISTRIBUTOR ROTOR

Lewis R. Hetzler, Ann Arbor, Mich., and Raymond A. Wilkins, Anderson, Ind., assignors to General Motors Corporation, Detroit, Mich., a corporation of Delaware

Application October 22, 1947, Serial No. 781,424

1 Claim. (Cl. 200—19)

1 This invention relates to the suppression of disturbances to radio receivers by automotive ignition apparatus. Heretofore, suppressors have been used with ignition apparatus in various ways to eliminate interference with radio receiving sets ordinarily used in homes or on automobiles; but it has been found that those suppressors do not eliminate interference by ignition apparatus with highly sensitive radio receiving sets, for example, television receivers.

It is an object of the present invention to provide suppression of ignition disturbance which is adequate to practically eliminate interference with highly sensitive radio sets. In the disclosed embodiment of the present invention this object is accomplished by the use of a distributor rotor whose spark gap electrode is provided by a resistance element.

Further objects and advantages of the present invention will be apparent from the following description, reference being had to the accompanying drawings wherein a preferred embodiment of the present invention is clearly shown.

In the drawings

Fig. 1 is a sectional view on an enlarged scale showing a distributor cap with a rotor constructed according to the present invention;

Fig. 2 shows a plan view of the rotor and a wiring diagram of the ignition system;

Fig. 3 is a sectional view on line 3—3 of Fig. 1; and

Fig. 4 is a perspective view of a part adapted to be attached to the suppressor resistance.

A distributor cap 10 has a central terminal 11 supporting a conducting button 12 connected through the terminal with the secondary winding 13 of an ignition coil C whose primary winding 14 is connected with the grounded end of the secondary winding 13 and with contacts 15 of the ignition timer T paralleled by a condenser 16. Primary winding 14 is connected by a switch 17 with a battery B. The timer contacts are controlled by an engine driven cam S which drives a distributor rotor R comprising a rotor block 20 of molded insulating material enclosing a metal insert 21 having a tubular rivet portion 22 by which a steel spring 23 and a copper connector 25 can be attached to the insert. Spring 23 supports a metal contact 24 engaging the button 12. Before assembling the rotor parts, a resistance element 26 of carbon or other suitable material having a high value of distributed resistance is attached to a thin copper disc 27 providing the electrode tip and to a suitable connector such as the part 25. For the purpose of

2 facilitating the attachment of parts 25 and 27 to the element 26, molten copper is sputtered on the ends of the element 26 to provide a surface which bonds readily with these parts by soldering or welding. The rotor block 20 has a recess 28 (Fig. 3) for receiving the element 26.

The function of element 26 is to retard capacity discharges of the capacity to ground of the wiring and parts electrically connected with the 10 spark gap in the distributor. We have discovered that the element 26 is most effective when located at the spark gap. Although the element 26 carries a tip 27, for all practical purposes the element 26 is at the spark gap and provides the 15 rotor distributing electrode as it moves past the distributor terminals 30 which are each connected with a spark plug 31 as indicated in Fig. 2. The electrode tip 27 which is used to increase the durability of the rotor is so small and it is 20 spaced from the rotor body 20 a distance of a plurality of times its thickness in order that its reduction of the effectiveness of the element 26 is practically negligible. The path of electrostatic flux between the tip 27 and ground represented by cam S which drives the rotor R is 25 indicated by dot-dash line ef in Fig. 1. Since the electrode 26 extends beyond the rotor body 20 a substantial distance, a substantial part of path ef is in an air gap. Therefore the practically negligible capacity, with respect to ground, of the tip 27 is due to the fact that the path of electrostatic flux is through air as well as to the fact that the mass of tip 27 is small. Therefore it is desirable that the rotor body 20 extend 30 toward the posts 30 no farther than is necessary to adequately support the electrode 26.

The suppressor element 26 is the most effective when located at the spark gap in the distributor for the following reason: Before the gap 40 at the end of the distributor rotor ionizes, energy is stored in any capacity that exists between the high tension path and ground. When ionization occurs, the energy which is stored in the capacities on the sparking side of the suppressing resistor is released without having to pass through the suppressor. If this capacity is kept at a 45 minimum this initial burst of energy is not sufficient to cause serious interference. The capacity to ground of the small electrode tip 27 is so small that ignition apparatus which includes the present rotor has practically no disturbing effect on even the most sensitive radio receivers, such as television receivers.

The resistance of the element 26 is usually in 50 the range of 5000 to 10,000 ohms. These limits

depend on engine performance and the degree of suppression required. Good results have been obtained with a resistor $\frac{3}{8}$ " in length and having 5000 ohms resistance and having an electrode tip of copper about .03" thick.

While the form of embodiment of the present invention as herein disclosed constitutes a preferred form, it is to be understood that other forms might be adopted, all coming within the scope of the claim which follows.

What is claimed is as follows:

An ignition distributor rotor having a nonconducting body adapted to be connected with a driving shaft, a contact supported by the body and adapted to engage the center contact of a distributor cap having a circular row of terminals for connection with spark plugs, and a spark gap electrode made of a material such as carbon having a relatively high value of distributed resistance supported by the body and connected with the contact and extending beyond the rotor body, and a conducting member of arc resisting material attached to the overhanging end of the

carbon electrode, said member having such small dimensions and being spaced from the rotor body a distance of a plurality of times the thickness of said member so that the capacity of said member with respect to ground is substantially negligible.
